UNITED STATES PATENT OFFICE.

SIMON KREGER, OF PHILADELPHIA, PENNSYLVANIA.

IMPROVEMENT IN CRUTCH-HANDLES.

Specification forming part of Letters Patent No. 116,603, dated July 4, 1871.

To all whom it may concern:

Be it known that I, SIMON KREGER, of the city of Philadelphia and State of Pennsylvania, have invented an Elastic Detachable Crutch-Handle, of which the following is a specification:

The object of my invention is to furnish a handle that can readily be applied to any crutch, and that will yield to the weight of the body and conform to the movements of the person using the crutch, so as to afford ease and comfort. A crutch supplied with my handle is materially lighter than a crutch which has a spring in its staff. In crutches of this character the spring is inclosed in a metallic ferrule, and is liable to become clogged up and rendered inoperative by the dirt or mud that penetrates its inclosure and adheres to the spring. My invention, likewise, cheapens the cost of the spring-crutch and increases its durability.

My invention is delineated in the accompanying drawing.

A is the shoulder-piece, that rests on the springs B B, which are sustained by the base-piece C. The springs B B are held in position by the rod D that passes through the base-piece and springs

into the shoulder-piece A. The springs may be kept in place by any other suitable device. In the under surface of the base-piece are sockets E E, into which fit the sticks that constitute the staff of the crutch, and the ends of said sticks may be secured in the sockets by thumb-screws or other mechanical means.

I expressly disclaim the use of an elastic strap or its equivalent in the construction of my crutch-handle; and I also disclaim resting the head of the crutch upon springs placed over the ends of the side pieces, or resting the ends of the head piece upon springs in which the side pieces are inclosed; but

I claim as my invention—

A crutch-handle, stationary on the staff when in use, but detachable therefrom at pleasure, and composed of a non-elastic shoulder-piece fitting under the arm-pit, and superimposed on springs held in place by rods or otherwise, and a base-piece, into which are inserted the ends of the side pieces that form the staff of the crutch.

Witnesses: SIMON KREGER.
